COMBINED SELECTIVE ADSORPTION-
CATALYTIC CRACKING PROCESSStephen F. Perry, Roselle, N. J., assignor to
Standard Oil Development Company, a corpora-
tion of Delaware

Application January 8, 1949, Serial No. 69,911

5 Claims. (Cl. 196—52)

1

The present invention is concerned with an improved process for the refining of petroleum hydrocarbon fractions. The invention is more particularly concerned with the processing of a hydrocarbon fraction utilizing an adsorption stage and catalytic cracking stage in combination one with the other. In accordance with the process of the present invention a petroleum fraction is catalytically cracked using a solid catalyst. The catalyst is removed from the cracking zone and regenerated in a regeneration zone. At least a portion of the catalyst from the regeneration zone is then passed through an adsorption zone wherein the regenerated catalyst contacts a petroleum fraction to remove therefrom the relatively more aromatic type constituents. This portion of the catalyst containing the adsorption constituents having a relatively high carbon to hydrogen ratio is then passed to the catalytic cracking zone. A preferred embodiment of the present process is to contact a hydrocarbon fraction boiling in the lubricating oil or kerosene boiling ranges with a catalyst; to remove the catalyst and to utilize the same to crack a hydrocarbon fraction boiling in the gas oil boiling range.

It is well known in the art to refine petroleum oils by distilling the crude or feed stream in order to segregate various hydrocarbon fractions such as those boiling in the gas oil boiling range, the kerosene boiling range and in the lubricating oil boiling range. Usually the practice is to crack the gas oil fraction by either a thermal or a fluid or fixed bed catalytic cracking operation. Temperatures and pressures, as well as feed rates may be varied depending upon the particular stock being cracked. Cracking temperatures are generally in the range from about 750—1000° F. while the pressures are in the range from atmospheric to 1000 pounds. Preferred cracking temperatures are in the range from about 850° F.—975° F. If a fluid operation is utilized any suitable cracking catalyst may be employed, as well as, any known means of fluidization. The catalyst particles vary in the range from about 20—200 microns in size.

When the gas oil fraction is processed in a catalytic cracking operation, the product stream contains a relatively large percentage of aromatics and olefins. While these aromatic constituents are very desirable in the petroleum fraction boiling in the motor fuel boiling range, they are undesirable with respect to the fractions boiling in the kerosene range. It is, thus, desirable to remove these aromatic fractions from certain products such as kerosene, and lubricating oils.

2

This is usually accomplished by various procedures such as an adsorption operation, an acid treating operation and the like. When solid adsorbents are utilized, it is necessary to regenerate the adsorbent usually by burning, solvent treating or an equivalent method.

In accordance with the present invention a combination process consisting of a cracking and an adsorption stage is utilized. The invention may be readily understood by the drawing illustrating embodiments of the same.

Referring to the drawing, a feed oil, which for the purpose of illustration is taken to be a crude oil, is introduced into distillation zone 10 by means of feed line 1. Temperature and pressure conditions are adjusted in distillation zone 10 to segregate; normally gaseous hydrocarbons, which are removed from zone 10 by means of line 2, a fraction boiling in the gasoline boiling range which is removed from zone 10 by means of line 3, a gas oil fraction which is removed by means of line 4, and a lubricating oil fraction which is removed by means of line 5. A higher boiling fraction may be removed from zone 10 by means of line 6. It is to be understood that zone 10 may comprise any suitable number and arrangement of distillation stages. It is also to be understood that the extent to which the crude oil is fractionated into various streams may be widely varied depending upon operating conditions and boiling ranges of the product streams desired. For the purpose of description it is assumed that the gas oil stream comprises hydrocarbon fractions boiling in the range from about 400° F.—700° F. and that the lubricating oil fraction boils in the range from about 650° F.—900° F.

In accordance with the invention the gas oil fraction is introduced into catalytic cracking zone 20 by means of line 4. Regenerated or fresh catalyst is introduced into the top of catalytic cracking zone 20 by means of line 7, and the spent catalyst withdrawn from the bottom of zone 20 by means of line 8. For the purpose of description it is assumed that the cracking catalyst comprises silica and alumina. Temperature and pressure conditions in zone 20 as well as oil and catalyst feed rates are maintained within a range to secure the desired cracking of the gas oil fraction and to produce lower boiling constituents. A product stream is withdrawn overhead from zone 20 by means of line 9 and introduced into distillation zone 30. Uncondensed gases are removed overhead from zone 30 while a cracked gasoline is withdrawn by means of line 11. Heavier higher boiling constituents are removed from zone 30

by means of line 12. It is to be understood that suitable cooling, condensing and heat exchange equipment is utilized.

The spent catalyst is withdrawn from zone 20 by means of line 8 as hereinbefore described and introduced into regeneration zone 40. The catalyst is regenerated in zone 40 preferably by burning the catalyst with air which is introduced into zone 40 by means of line 13. Steam is also utilized and is introduced by means of line 14. A portion of the regenerated catalyst is withdrawn from the bottom of zone 40 by means of line 7 and returned to zone 20. In accordance with the present invention a portion of this catalyst is segregated by means of line 15, passed through a heat exchanger zone, introduced to cyclone separator 16 and then passed to contacting zone 50.

The lubricating oil fraction withdrawn from zone 10 by means of line 5 is preferably mixed with a diluent comprising liquified propane, butane or a light naphtha which is segregated in zone 30 and introduced into line 5 by means of line 17. The lubricating oil is introduced into contacting zones 50 and 60 alternately. In zone 50 and in zone 60 the lubricating oil fraction contacts the regenerated adsorbent under conditions to remove the more aromatic type constituents, the sulfur compounds, resins and gum-forming materials selectively. Thus, the quality of the lubricating oil fraction is materially improved. Continuous and countercurrent contacting of the diluted lubricating oil fraction with the adsorbent is preferred. It is to be understood however a single stage continuous contacting unit may be employed. Batch operations utilizing two or more zones also may be used.

The spent adsorbent is separated from the treated lubricating oil fraction in filter zone 80 where it may also be washed with additional diluent introduced through lines 17 and 24. The treated oil diluent and wash liquid removed from filter 80 are passed by means of line 18 through heater 19 and introduced into distillation zone 70. Temperature and pressure conditions are adjusted in zone 70 to remove overhead by means of line 21 the diluent which may be handled as desired but is preferably condensed and recycled to contacting zones 50 and 60. The high viscosity lubricating oil fraction is withdrawn from zone 70 by means of line 22 and may be further treated as desired.

The adsorbent is withdrawn from filter 80 by means of line 23 and is introduced into cracking zone 20 by means of line 7. If desired, this stream may be subjected to a mild steaming or purging operation prior to introducing the adsorbent into the reactor. This steaming or purging operation is conducted under conditions such that the loosely held diluent is removed and the adsorbed aromatic fraction is retained.

The more aromatic type constituents which are retained on the spent adsorbent has very poor lubricant qualities but is an excellent feed stock for a cracking operation. The resulting gasoline has a relatively high anti-knock value. Similarly, when employing the adsorbent step for kerosene refining, the aromatic kerosene fraction is retained by the adsorbent and recycled to the cracking step. Thus, the quality of the kerosene, as well as the quality of the resulting gasoline is improved. The present invention comprises a combination operation wherein aromatic constituents are removed from a feed oil and returned to a cracking zone under conditions so that both the quality of the heavier fraction and the quality

of the gasoline fraction is materially improved. The invention is specifically adapted to the production of high quality kerosenes, lubricating oil and gasolines.

The invention is generally concerned with the catalytic cracking of hydrocarbon constituents boiling in the gas oil boiling range in the presence of adsorbed aromatic type constituents removed from a petroleum fraction boiling either above or below the gas oil boiling range. It is preferred that the aromatic constituents present be secured from a heavier boiling fraction, as for example, a fraction boiling in the range from about 675° F. to 900° F. A satisfactory operation is also attained when the aromatic constituents present in the catalytic cracking zone are segregated from kerosene fractions boiling in the general range from about 375° F. to 550° F. In general it is preferred that the gas oil fraction boil in the range from about 400° F. to 700° F.

The preferred catalyst comprises a silica-alumina catalyst particularly, a catalyst which comprises about 80-90% SiO_2 and from 10-20% Al_2O_3 . A particularly desirable catalyst comprises 85% SiO_2 and 15% Al_2O_3 .

The amount of catalyst segregated from the regeneration zone and passed to the adsorption zone may vary considerably. However, in general it is preferred that from about 20-50% of the catalyst withdrawn from the regeneration zone is passed through the adsorption zone.

The quantity of catalyst used in the adsorption zone when contacting a petroleum oil boiling in the lubricating oil boiling range should vary in the range from about 2-6 parts by weight of catalyst per 1 part by weight of oil. The volume of diluent used should be from 2-10 parts of diluent per part of oil. The temperature employed in the adsorption zone may be in the range from about 80 to 300° F., although it is preferred that the temperature be in the general range from 125 to 150° F. The time of contact should be in the range from about 5 to 30 minutes, preferably from about 15 to 20 minutes. When the oil being contacted in the adsorption zone boils in the kerosene boiling range the amount of catalyst used should be in the range from 0.5 to 1 part by weight of catalyst per 1 part by weight of oil. The amount of diluent used under these conditions should be in the range of from 1 to 3 parts of diluent per part of oil. The temperatures used are similar to those used when contacting lubricating oils.

It is claimed:

1. Improved process for the production of a high quality lubricating oil and a high quality cracked gasoline from a petroleum feed oil, which comprises segregating said petroleum feed oil into a petroleum fraction boiling in the gas oil boiling range and into a petroleum fraction boiling in the lubricating oil boiling range, catalytically cracking said fraction boiling in the gas oil boiling range in a cracking zone with a cracking catalyst under conditions to produce a cracked gasoline, separating the cracking catalyst and regenerating the same, segregating a portion of said regenerated cracking catalyst and contacting said petroleum fraction boiling in the lubricating oil boiling range with said catalyst under conditions to adsorb thereon the more aromatic type constituents, thereafter separating said catalyst from the oil and recycling said cracking catalyst containing said adsorbed constituents to said cracking zone.

2. Process as defined by claim 1 wherein said gas oil boils in the range from about 400-700° F. and wherein said lubricating oil boils in the range from about 675° F. to 900° F.

3. Process as defined by claim 2 wherein said catalyst comprises from about 80-90% SiO_2 and 10-20% of Al_2O_3 .

4. Improved process for the production of a high quality lubricating oil and a high quality cracked gasoline from a petroleum feed oil, which comprises segregating said petroleum feed oil into a petroleum fraction boiling in the gas oil boiling range and into a petroleum fraction boiling in the lubricating oil boiling range, catalytically cracking said fraction boiling in the gas oil boiling range in a cracking zone with a cracking catalyst under conditions to produce a cracked gasoline, separating the cracking catalyst and regenerating the same, segregating a portion of said regenerated cracking catalyst, adding a diluent to said petroleum fraction boiling in the lubricating oil boiling range, and contacting said petroleum fraction with said segregated portion of regenerated catalyst under conditions to adsorb thereon the more aromatic type constituents, separat-

10

ing said catalyst from the oil and recycling said catalyst to said cracking zone.

5. Process as defined in claim 4, wherein said catalyst recycled to said cracking zone is treated with steam in a manner to remove the diluent and in a manner that said catalyst retain said adsorbed constituents.
